SNAP FASTENER

Forrest G. Purinton, Waterbury, Conn., assignor
to The Patent Button Company, Waterbury,
Conn., a corporation of Connecticut

Application March 17, 1941, Serial No. 383,813

6 Claims. (Cl. 24—208)

My invention relates to new and useful improvements in snap fasteners, and particularly to the socket element thereof.

One of the objects of the present invention is to produce a new and improved socket member that is arranged to protect the resilient fingers when the garment with the fasteners thereon is passed through the wringer or is being ironed.

A further object of the invention is to produce a socket wherein the prongs that pass through the garment are on the socket member rather than on the ring member and are protected by guards until attached to the garment.

As is well known, these snap fasteners are attached (permanently) in a rapid manner by automatic machines, and another object, therefore, of the present invention is to so arrange the socket element that the upstanding prongs thereof (before the socket element is attached) are protected by guards to thus keep the prongs from interfering and snarling with the prongs of adjacent elements when they are going through the manufacturing operations in bulk, such operations being the cleaning, plating, and tumbling to remove the burrs.

Furthermore, these guards will facilitate the attaching operation in that the sockets will not become tangled with each other in the hopper and the flow of these sockets through the slots in the hopper to the raceway and attaching station will be more uniform.

Still another object of the invention is to preferably provide the socket of the snap fastener with a multiplicity of hills or depressions (depending from which face the socket is viewed), the bottoms of these depressions extending below the plane of the spring fingers to thus protect the same when the socket is passing through a wringer. At the same time, the metal between the depressions may be cut to provide the guards that will prevent the prongs of the socket member from tangling with each other before the socket member is attached to the garment. These guards, however, will be pushed back out of the way during the attaching operation.

With these and other objects in view, the invention consists in certain new and novel arrangements and combination of parts, as will be hereinafter more fully described and pointed out in the claims.

Referring now to the drawings showing a preferred embodiment,

Fig. 1 is an enlarged sectional view of the fastener as attached to the garment, the stud or

male member, however, being separated from the socket;

Fig. 2 is a similar sectional view but with the members fastened together;

Fig. 3 is an enlarged top view of the pronged socket element;

Fig. 4 is an enlarged bottom view of the same;

Fig. 5 is an enlarged sectional view taken on the line 5—5 of Fig. 3;

Fig. 6 is an enlarged sectional view taken on the line 6—6 of Fig. 3;

Fig. 7 is a top plan view of the locking ring element;

Fig. 8 is a bottom plan view of the same element;

Fig. 9 is a sectional view thereof, the dotted lines showing the plastic as molded therein; and

Fig. 10 is a schematic view showing sections of the locking ring, the garment, and the socket member before assembly.

Referring now for the moment to Figs. 1 and 2, there is shown a male element or stud 1 having a ring 2, which stud is secured to part of a garment 3. It will be understood that this stud or male member per se does not form a part of the present invention, as my improved socket may equally as well be used with any other similar male element or stud.

The invention resides in the formation and construction of the socket element. This element may be seen more in detail in Figs. 3 to 6, inclusive.

Referring for the moment, therefore, to Figs. 3 to 6, there will be seen my improved socket construction, which consists in the arrangement of a small plate 4 circular in outline and, of course, of relatively thin metal of the desired resiliency. These snap fasteners are generally made of brass and may then be nickelized or otherwise finished to provide a pleasing appearance.

The plate 4 is preferably provided with six upstanding triangularly-shaped prongs 5 arranged around the periphery, as may be seen in the several views.

There is a central aperture, as at 6, as this plate (socket) with its spring fingers, to be shortly mentioned, is snapped over the stud or male member 1, heretofore-mentioned, as is the ordinary practice.

Glancing for the moment at Figs. 5 and 6, to understand the formation of this plate and reading from the right-hand side of the figures, it will be seen that the plate 4 extends in a horizontal plane at its periphery, as at 7, and then curves slightly upwardly, as at 8, to the plane 9,

where it is then bent downwardly, forming the vertical wall 10. The metal is then bent inwardly to form a bead 11, thus becoming a part of the spring fingers, which are to grip the stud 1 when the snap fastener is snapped into place.

The vertical wall 10 is then radially slotted around its periphery, as at 12, as may be seen in Figs. 3, 4, and 6, so that the desired resiliency is provided for the resultant segments or spring-gripping fingers 13.

Beyond the central vertical wall 10 are formed the guards 14, which radiate from the center of the socket and are disposed in radial lines with the respective prongs 5 arranged around the periphery of the plate 4. These guards 14 are bent upwardly (Figs. 5 and 6) from their normal plane and extend outwardly to but a short distance from the apices of said triangular peripheral prongs 5, that is, they extend in this upward guarding position until the prongs are forced through the garment and into their locking ring, as will shortly be mentioned.

Spaced directly behind the slots 12, as may be clearly seen in Figs. 3 and 4, are the hills 15, which hills are likewise spaced midway the guards 14. The tops of these hills 15 extend (Fig. 4) in a plane slightly above the plane of the spring fingers 13, so that when the garment is ironed or put through a wringer or drier, these hills will protect the spring fingers 13 from being damaged.

By providing the hills rather than by forming a raised ring slightly back from the fingers to protect the spring fingers, as is the conventional arrangement, sufficient metal is left between the hills to provide material stock for the guards 14, as heretofore-mentioned.

Thus, by providing the hills above-mentioned, not only are the spring fingers well protected from damage in ironing but space in the plate is provided to form these integral guards, which are to prevent the prongs from catching with the mass of sockets when in a hopper, etc., as will now be set out.

In the manufacture of the socket element, that is, in its later operations, such as cleaning, plating, and tumbling to remove any burrs or fins, the socket with its upstanding sharp triangular prongs, unless the prongs are guarded, has a tendency to lock or tangle with the surrounding sockets and the prongs of one socket may catch in the central aperture of an adjoining socket, thus making the sockets relatively hard to plate or tumble or clean. However, by providing the guards 14, as shown, the latter will prevent these sharply pointed prongs from interlocking or tangling with other sockets.

Again, inasmuch as these sockets are to be thrown into a hopper or cup of an attaching machine (not shown) and there tumbled until they register with and pass through the radial slots in said hopper and down a feed chute to an attaching station, unless the prongs are guarded, the sockets in bulk are likely to interlock (tangle) and not become disengaged and so be continuously tumbled and not pass out of the radial slots in the cup of the hopper, as only one socket may pass out at a time when in registry with its slot.

However, by providing these guards, there is far less likelihood of the sockets in the hopper becoming interlocked and when tumbled will more quickly register with the slots in the hopper to then pass down the chute to the attaching station.

Referring now to the means for clamping or locking the socket to its garment, which forms

the subject-matter of a separate application, there may be seen in Fig. 9 a metal ring 16 with its overhanging wall 17 and the underlying rim 18 that terminates short of the inner periphery of the wall 17. As will also be noticed, there is a space 19 provided between the rim 18 and the overhanging wall 17, so that the metal prongs 5 which, as will be mentioned, are distributed around the periphery of the socket plate may be driven through the cloth 20 (Figs. 1, 2, and 10) to impinge on the under surface of the overhanging wall 17 and be forced into the heretofore-mentioned space 19 underlying the said overhanging wall. The ring 16 also preferably has an inner bead 21 about its top surface so that the latter may be embedded in a plastic head 22, as may be readily seen in Fig. 10.

This plastic head 22 may slightly overlie the inner periphery, as at 23, of the ring 16 and will also extend downwardly, as at 24, within the side walls of the ring, so that the cloth or material 20, when clamped between the ring and the socket element, may follow the inner contour of this plastic head, as may be seen in Figs. 1 and 2. By embedding the bead 21 well within the plastic head 22, even should the plastic shrink, there is no possibility of its becoming disengaged from its ring.

In Fig. 10, I have, for purposes of illustration, shown the socket in a position below the garment and the ring above the garment. It will be understood that the prongs 5 will, when the ring and socket member are forced together, pass through the garment, impinge on the under surface of the overhanging wall 17, and be directed into the heretofore-mentioned receptive space 19 to thus securely clamp the socket and the ring to the garment, as shown in Fig. 1. At the same time, the guards 14 which have served their purpose, to wit, prevented the sockets, when in bulk, from becoming tangled, etc., will be pressed downwardly against the cloth and out of the way, so that the prongs 5 may be well gripped within their ring, as clearly shown in Figs. 1 and 2.

The cloth 20 will be tightly gripped between the ring and the socket element, and after once attached, will always remain in its attached position. The socket member may be quickly snapped over the stud 1 after the latter has been attached or may be easily unfastened, similar to any other snap fastener.

From the foregoing, it will be seen that I have provided a new, novel, and efficient form of snap fastener having the usual inner spring fingers and also having portions of the metal of the plate extending in a plane below that of the fingers (Fig. 1) to protect the same when the garment is being ironed. I have further provided the radially extending guards, which greatly facilitates the manufacturing operations of the fastener and also facilitates the attaching operations, as the prongs are not as likely to tangle with other sockets when the said sockets are being tumbled before being passed from the hopper to an attaching station.

I have also provided a ring to receive the prongs of the socket and to tightly clamp the socket to its garment.

By providing the hills or depressions (depending on from which face the socket is viewed), rather than providing a continuous wall, sufficient metal is left to form the guards, which serve their useful purpose before the socket is attached and which guards will also tightly bear against the cloth after the socket is attached, "attach-

ing" here meaning the permanent attaching rather than the snapping of the socket on its male member.

Having thus described my invention, what I claim as new and desire to secure by Letters Patent is:

1. In a snap fastener, a socket element including a plate circular in outline and provided with a plurality of prongs extending at right angles to the plate and spaced about the periphery, the plate provided with a central aperture and the walls of the aperture arranged to form spring fingers and adapted to lock over the stud of a male element of the snap fastener, a plurality of depressions also spaced around the central aperture and extending in a plane below that of the spring fingers to thereby protect the same, a plurality of guards formed integral with said plate and extending upwardly and toward the apices of the said prongs, and said fingers adapted to be forced downwardly with relation to the prongs and out of the way when the snap fastener is permanently secured to its garment.

2. In a snap fastener, a socket element including a plate circular in outline provided with a plurality of attaching prongs extending at right angles to the plate and spaced about the periphery, the plate provided with a central aperture and the walls of the aperture being slotted to form spring fingers which are adapted to lock over the stud of a male element of the snap fastener, means formed in the metal behind the forward edges of said fingers that extend in a plane below that of the forward edges of said spring fingers to protect the same, integral guards interspaced between said means and extending toward the apices of said prongs and raised from the normal plane of said plate, the said guards adapted to be forced back into the normal plane of said plate when the socket element is being permanently attached to its garment.

3. In a snap fastener, a socket element including a plate circular in outline and provided with a plurality of prongs extending at right angles to the body of the plate and said prongs spaced about the periphery of the plate, the plate provided with a central aperture and the walls about the aperture extending also substantially at right angles to the body of the plate and having a horizontally extending inner peripheral bead, the said walls being radially divided to form spring fingers about the aperture and said spring fingers adapted to snap over the stud of the male member of the snap fastener, a plurality of radially extending guards cut in the body of the plate

and their outer ends extending upwardly toward the apices of said prongs, a portion of the metal between each of the said guards extending in a plane below the horizontal plane of the said bead when the socket is attached to thereby protect the said spring fingers, and the guards adapted to be forced back substantially in the plane of the body of the socket when the socket member is being firmly attached to its garment.

4. A socket member for a snap fastener including a plate having a central aperture and a plurality of spring fingers forming the peripheral wall about said aperture, a plurality of vertically extending prongs spaced about the periphery of the plate, a plurality of guards extending radially from the central aperture and bent upwardly from the normal body of the plate and extending toward the apices of the respective prongs, a plurality of indentations formed in the plate and disposed between the respective guards and lying in a plane lower than the lower ends of the spring fingers when the socket is in an attached condition, a circular ring to receive and hold the said prongs, and the said guards being bent toward the bases of said prongs when the said socket member of the snap fastener is attached to its garment.

5. In a socket member including a plate having a central aperture, spring fingers defining the walls about the central aperture, prongs disposed about the outer periphery of the plate and extending at an angle to the body of the plate, metal guards struck up from the body of the plate to protect the prongs and metal depressions formed in the plate between said guards to protect the said spring fingers, and a ring element adapted to receive the said prongs when the socket is attached and the guards adapted to be forced downwardly toward the bases of the prongs during the said attaching operation.

6. In a snap fastener, a socket member including a plate having a central aperture, spring fingers defining the walls about the central aperture, prongs disposed about the outer periphery of the plate and extending at an angle thereto, metal guards struck up from the body of the plate and extending toward said prongs to prevent the prongs from tangling with other socket members when the said socket members are in a hopper, a ring element adapted to receive the said prongs when the socket is attached, and the guards adapted to be forced downwardly toward the bases of the prongs during the said attaching operation.

FORREST G. PURINTON.
